WILLIAM JARDEN.

U6-211. OR D 14386 EX

UNITED STATES PATENT OFFICE.

ADOLPH PETZOLD, OF PHILADELPHIA, PA., ASSIGNOR TO JOHN H. BROMLEY, JOSEPH H. BROMLEY, AND EDWARD BROMLEY, ALL OF SAME PLACE.

DESIGN FOR A RUG.

SPECIFICATION forming part of Design No. 14,386, dated October 20, 1883.

Application filed August 25, 1883. Term of patent 3½ years.

To all whom it may concern:

Be it known that J. ADOLPH PETZOLD, a citizen of the United States, and a resident of Philadelphia, Pennsylvania, have invented and produced a Design for Rugs, &c., of which the following is a specification.

The nature of my invention is fully set forth in the accompanying photographic illustration, to which reference is made.

What I claim as my invention is—

The design for rugs, as shown.

Witnesses: ADOLPH PETZOLD,

ELIAS S. LITTLE,

WILLIAM JARDEN.
